CAST CUTTING DEVICE

Chester E. Waxlax, Los Angeles, Calif.

Application November 6, 1945, Serial No. 626,990

5 Claims. (Cl. 128—91)

1

My invention relates generally to surgical casts used in healing broken bones and more particularly to a device for removing these casts without injury or inconvenience to the patient.

The present application is a continuation-in-part of my co-pending application, Serial No. 577,007, filed February 9, 1945, now abandoned, and entitled Cast Cutting Device.

Heretofore the conventional practice in removing casts has been to employ large shears or other cutting tools not integrally bonded to or positioned in the cast and hence awkward to handle and liable to gouge or cut the patient, so that he very often experiences more pain from the removal of the cast than from the broken bone. Furthermore, these prior art devices have usually been cumbersome and expensive and not universally adaptable.

The major object of my invention is to provide a cast cutting device which is simple to operate and which can be used for all types of casts irrespective of the part of the body embraced therein.

A further object of my invention is to provide a device of this character which becomes embedded in the cast so that it becomes an integral part thereof and consequently is immediately available for use.

A more specific object of the invention is to provide a cast cutting means adapted to be included within a surgical cast and to be positively positioned therein and which has sufficient flexibility that it can be readily formed around joints or other curves necessitated in the cast, in which position it will operate successfully without danger of injury to the patient.

An additional object is to provide cast cutting means which produces a clean, uniform cut of small dimension so that the cast may be placed back on the limb and secured together again.

Still another object of my invention is the provision of a novel flexible blade which is particularly effective where relatively hard casts are employed.

These and other objects of my invention will become apparent from the following description of a preferred form thereof and by reference to the accompanying drawings, in which:

Fig. 1 is an elevational, partially sectioned view of a human foot encased in a plaster cast in which is embedded a cast cutting device constructed according to my invention;

Fig. 2 is a partial transverse section of the cast and cutting device taken on the line 2—2 in Fig. 1;

2

Fig. 3 is a section similar to Fig. 2 taken after the cutting device has been operated to sever the cast;

Fig. 4 is a perspective sectioned view showing the cutting device prior to its being embedded in the cast;

Fig. 4a is an enlarged cross section of one form of cutter employed taken on the line 4a—4a in Fig. 4; and

Fig. 5 is a plan view of a portion of the protective strip which is employed in the cutting device.

In general, my invention contemplates means housing a flexible blade in a cast which may be operated in saw-like fashion to sever the cast without injury to the patient. The cast is formed on the body overlying the cutting device which is thus embedded in the cast. When it is desired to remove the cast, the blade is merely reciprocated longitudinally in the passage with a conventional sawing motion until it has cut up through the cast to sever the same.

Referring now to the drawings which illustrate a preferred form of my invention, and particularly to Fig. 4 thereof, it will be seen that numeral 9 indicates a base strip or layer of adhesive tape of the usual surgical variety disposed with its adhesive face uppermost. Upon the upper face of tape 9 is a flat flexible flesh protective strip 10, preferably of metal or other abrasion resisting material, which adheres to the upper face of the tape 9. A blade receiving passage centrally disposed along the upper face of protective strip 10 is formed by punching and bending up a series of guide ears 11 alternately disposed along the sides of the passage. The ears 11 form continuous guiding means or housing for a blade 12 held therebetween and are preferably of arcuate cross-section in order that the faces adjacent the blade shall present a gliding surface to the moving blade to thereby prevent damage to the latter, or its catching on sharp edges of the ears 11 during operation. The passage formed between the guide ears 11 is covered with a layer 13 of crinoline, surgical gauze, or a similar fabric which is painted with a moisture-proof solution of adhesive material such as collodion, thus to prevent the plaster used in forming the cast from entering and obstructing the passage. The stiffness of the upstanding ears 11 is such as to prevent crushing of the housing formed thereby due to pressure of the applied cast material. The fabric layer 13 extends beyond the edges of the adhesive tape 9 so as to insure positive binding with a plaster cast 14.

which is formed thereon. This adhesive and moisture-proof layer serves the additional purpose of bonding all the elements together into an integral unit comprising protective strip 10, adhesive tape 9, and gauze strip 13.

The passage formed above the upper surface of protective plate 10 carries a thin blade 12 preferably twisted to have helical edges and mounted therein for longitudinal movement, the relative sizes of the blade and passage and the alternate disposition of guide ears 11 being such, however, that while the blade can be readily moved longitudinally of the passage, it will not slide out of its own weight.

While I may form the blade 12 of a single 15 twisted strip similar to those used in the previous art for surgical saws and the like, I prefer in order to provide a blade having greater strength and better cutting qualities to form it of two strips placed face to face, having beveled and sheared edges and twisted so that the edges follow a helical curve as illustrated in Fig. 4. The beveling of the edges is best seen in Fig. 4a. The blade 12 is flexible so that it follows the protective strip assembly above described, and can be bent around curves of relatively small radii such as bent elbows, knee joints, or the like. The ability of the device to conform to both concave and convex body contours is particularly illustrated in Fig. 1. It will be apparent, however, that the metal strip 10 and the fabric layer 13 cemented thereto provides an adequate protective bearing surface and guide passage for the blade 12 in all positions of use.

Referring now to Figs. 1, 2, and 3, the numeral 15 indicates a foot which is to be encased in a cast, and the numeral 14 indicates a cast formed thereon by any suitable method, such, for example, as built-up layers of gauze and plaster, plastic, or the like.

It is a frequent practice in the use of surgical casts to replace the cast after it has been cut away for an examination. Such an operation requires the use of two or more cutting devices placed at appropriate points around the circumference of the cast as will be described herein. In the case shown in Fig. 1, it is desired to cut the cast 14 into two lateral half portions for removal from the foot 15. To accomplish this, two cutting assemblies are used—one in front and one in back of the foot as shown.

In the use of my device, two assemblies as shown in Fig. 4 are placed upon the limb 15, as seen best in Fig. 1, and the first layer of bandage and plaster is wrapped around the limb in conventional manner. The plaster will of course adhere to the overlying fabric cover layer 13 of each assembly, which becomes impregnated with the plaster, thus making the cutting devices integral parts of the plaster cast itself. The cast 14 is then built up in usual manner until the required thickness is obtained, it being noted that the sections of cutting device integrally embedded in the cast are somewhat longer than the cast so as to leave two ends 16 and 17 of each assembly extending beyond the ends of the cast. These ends are then bent back over the cast and preferably held in place by suitable means, such as strips of adhesive tape 18 and 19, respectively.

When it is desired to remove the cast 14, the end 16 and 17 of each cutting device are bent back to substantially their original position, and suitable handles are fastened to the blade so that it can be pulled in either direction. By then

sawing the blade back and forth, while at the same time maintaining an outward pull thereon with respect to the cast, the blade cuts up through the cast, starting at the ends thereof and working toward the center to produce a cut such as indicated by the numeral 20 in Fig. 3. It will be noted that the cut 20 is relatively small and regular so that, if desired, the cast may be put back together again.

It will be apparent, of course, that if it is desired to form a large cast having a considerable area in which it is desired to subsequently form an observation window, a plurality of the cutting devices shown herein may be embedded in the cast with their ends upstanding therethrough to form any desired pattern, such as, for example, a triangle or a rectangle. After the cast has set and it is desired to open a window therein, it is merely necessary to attach handles to the free ends of the various blades outlining the window area and saw through each boundary line, whereupon, the area bounded by the blades can be lifted out and replaced as desired.

It will be seen that a guide passage for the blade must, for satisfactory operation, constrain the cutting direction thereof so that it may only move outwardly through the cast and not inwardly into the flesh within the cast. It is also essential that the guide be flexible and hence able to conform to body contours. Previous guide means of this type lacked flexibility, or if flexible, did not provide an adequate guide for the cutting member. For example, a single flat strip having no lateral guide members would be flexible but would not prevent the blade from cutting sideways off the strip and thence into the body. On the other hand, channel-shaped metal guides having continuous side walls are relatively rigid and hence tend to bridge over concave portions 40 of the body, thus leaving voids in the cast under the cutting device or leaving portions of the cast inaccessible to the saw. Furthermore, such rigid members tend to rest against the body only at certain points hence concentrating the pressure and causing irritation at these points. My invention overcomes all of the just-mentioned difficulties by providing a completely flexible flesh protective and guide means which nevertheless assures positive grinding of the blade and protection of the patient.

As previously stated, one of the chief advantages in my invention resides in the fact that the blade passage and its flesh protective strip are integrally formed with the plaster cast and have sufficient flexibility in their original state that they may be bent around relatively sharp corners and the blade operated without fear of cutting into the patient. Furthermore, by having all of the various parts combined in a unitary or integral structure and having all the elements therein of a nature to insure a perfect bond between the cutting assembly and the plaster cast, it is unnecessary to press the cutting unit against the body within the cast in order to operate it. If, as is often the case, the swollen and distended condition of the limb within the cast diminishes during convalescence, the cutting device still remains bonded into the plaster cast and does not fall away therefrom as has been the case with previously used devices of this nature. Thus, it will be seen that my device can be operated to remove the plaster cast with a minimum of discomfort to the patient.

While the form of my invention shown and described herein is fully capable of attaining the

objects and providing the advantages heretofore stated, it is to be understood of course that it is merely illustrative of the broad features of my invention as defined by the appended claims.

I claim:

1. A cast cutting device which includes: a longitudinally extending flexible abrasion resistant, flesh protective strip; a plurality of guide members formed in said strip projecting upwardly therefrom, longitudinally spaced from each other and arranged in two laterally spaced rows, whereby to form a passage along the upper face of said strip; a second flexible strip supported on the upper ends of said guide members and extending longitudinally above said passage to cover and enclose the same; and a blade disposed within said passage and adapted to be reciprocated longitudinally thereof.

2. A cast cutting device which includes: an underlying flexible flesh protective strip; a housing formed adjacent the upper face of said strip along its length, said housing comprising a plurality of separate upturned members formed in said strip, said members being longitudinally spaced from each other and arranged in a pair of laterally spaced rows to define a longitudinal passage therebetween; a strip of adhesive tape disposed beneath said protective strip with its adhesive face in contact therewith and its edges extending beyond the sides of said protective strip; a layer of gauze overlying said passage, and adhesive tape and extending beyond the sides of the latter; and a flexible blade disposed in said passage for longitudinal movement therein.

3. A surgical appliance which includes, in combination: a surgical cast; and means embedded in said cast for severing it which comprises a flexible flesh protective strip adapted to resist abrasion with a blade receiving housing formed on its upper face, said housing comprising a plurality of separate upturned members formed in said strip, said members being longitudinally spaced from each other and arranged in a pair of laterally spaced rows to define a longitudinal passage therebetween, and a strip of fabric overlying said passage and bonded to the inner face of said cast by the natural adhesive characteristics of the material of said cast.

4. A cutting device adapted to be embedded in a surgical cast and bonded thereto which includes: a flexible flesh protective strip adapted to resist abrasion and to follow the contours of a body member within said cast; upstanding portions formed in said strip and projecting away from said body, said upstanding portions being

alternately disposed along the edges of said protective strip whereby to form a centrally disposed passage along a face of said strip opposite a body-adjacent surface; a bonding layer disposed across the outer ends of said upstanding portions whereby to cover said passage; a flexible cutting blade disposed within said passage and adapted to be reciprocated longitudinally thereof; and a bonding medium applied to said protective strip and said bonding layer whereby to integrally bond said bonding layer and said protective strip.

5. A cutting device adapted to be embedded in a surgical cast: a flexible flesh protective strip adapted to resist abrasion and to lie adjacent to and follow the contours of a body member within said cast; upstruck ear portions formed in said strip and projecting outwardly from said body member, said ear portions being alternately disposed along the edges of said strip whereby to form a centrally disposed passage therebetween and along a face of said strip opposite a body-adjacent surface; a length of adhesive tape disposed between said body member and said strip with its adhesive face in contact with the latter and its edges extending beyond the sides thereof; a gauze ribbon disposed across the ends of said upstruck portions and in contact with said adhesive tape with its edges extending beyond the sides of the latter; a bonding medium applied to a portion of said ribbon to cause it to adhere to said protective strip and to render said portion of the ribbon impervious to the material of said cast; and a flexible cutting blade disposed within said passage and adapted to be reciprocated therein whereby to sever said cast.
